UNITED STATES PATENT OFFICE.

CHARLES W. COFFIN, OF PORTLAND, MAINE.

AMUSEMENT DEVICE.

1,262,579.

Specification of Letters Patent. Patented Apr. 9, 1918.

Application filed February 19, 1917. Serial No. 149,427.

To all whom it may concern:

Be it known that I, CHARLES W. COFFIN, a citizen of the United States, and resident of Portland, county of Cumberland, State 5 of Maine, have invented an Improvement in Amusement Devices, of which the following description, in connection with the accompanying drawings, is a specification, like characters on the drawings representing 10 like parts in each of the several views.

This invention relates to amusement devices or games in the nature of miniature or parlor, bowling alleys or the like. In particular the invention has to do with 15 miniature bowling alleys and the like wherein a resilient or elastic transverse buffer or impinging member is provided against which the ball is caused to impinge so as to rebound back across the alley to the pins at 20 the other end thereof. A prime object of the invention is to supply a device of this character equipped with an improved form of resilient, ball rebounding element at one end thereof, of a type adapted to provide 25 for a rebounding of the ball within the required range, accurately and with precision, so that when the ball is properly directed thereagainst, it may be made to rebound in a definite direction to reach a pin or pins at 30 any particular location. A further object is to provide a device of this kind that has a specially formed ball rebounding element of a nature to require some little skill to insure the rebounding of the ball in a 35 definite manner, and that is directly and closely responsive, to a large extent, on the skill of the player. The foregoing and other objects and features of the invention will be better understood from the following 40 detailed description taken in connection with the accompanying drawings and will thereafter be pointed out in the appended claims.

Referring to the drawings:

45 Fig. 1 is a side elevation of device embodying the invention.

Fig. 2 is a plan view on a somewhat larger scale.

50 Fig. 3 is a central lengthwise section on line 3—3.

Fig. 4 is a transverse section of line 4—4 of Fig. 2.

Fig. 5 is a plan view of the ball guiding device shown in Fig. 1, and;

55 Fig. 6 is a plan view showing the preferred form of rebounding element.

The base 10, preferably of oblong rectangular form has the long and relatively narrow plane surface or alley 11, on the top thereof, with gutters 12 at each side leading 60 to a pit 13, formed in the base in the forward end of the alley. Side and end rails 14, 15, respectively, are supported by posts 16 upstanding from the corners and intermediate portions of the base, these rails being spaced apart and from the base vertically so as to constitute a guard or fence around the alley. At its forward end the alley 11 may be provided with indicating spots 17 to denote the proper locations for 70 the ten-pins 18.

Adjacent the rear end of the alley and extending transversely thereof is a ball rebounding element against which the ball "B" is projected to cause it to rebound 75 against the pins 18. The provision of a ball rebounding element suitable for this purpose presents a special problem since it is important that it be of a nature on the one hand to require some little dexterity on the 80 part of the player to attain proficiency, while on the other hand it should be of a character responsive to the skill of the player in large measure, so that skilful manipulation and projection of the ball there- 85 against will insure a rebound in a definite, predetermined direction. Thus with a re- 90 siliient cushion or edge with a solid backing extending straight across the end of the alley, the game would not be sufficiently dif- 95 ficult to be interesting, since if a ball be sent down the alley striking the cushion squarely, it would return on the same line that it traversed in going to the cushion. On the other hand a rebounding device such as a 95 rubber band held taut across the alley is so uncertain in its rebounding action on the ball that the use thereof does not to any considerable extent test the skill of the player and makes the game mostly one of chance, 100 such rubber or elastic band having a reactive effect on the ball that varies largely as to direction according to the speed of the projected ball, the degree of tautness of the band, the location on the band impinged by 105 the ball and other considerations. It is also necessary to take into consideration the long and relatively narrow character of the alley, and to provide for the requisite range of angular directions to the rebounding ball 110 for striking any one of the pin locations 17, with the limited range of projection of the

ball thereagainst the rebounding device that is obtainable.

I have found that for the fulfilling these requirements a rebounding device equipped 5 with a resilient edge extending in a gradual curve across the board, is suitable, this resilient edge having a firm or relatively rigid back throughout its extent adapted to prevent any substantial distortion or bodily 10 yield thereof. For this purpose I may provide as shown, a backing block or strip 19, which may be of wood extending across the rear end of the alley between the post 16, and suitably secured in place as by pins 20. 15 The front edge of this block is concaved on a curve which preferably has as its radius approximately the distance therefrom to the central portion of the spot space 17. A resilient rebounding edge 21, preferably of 20 rubber is set into this concaved base, which has an inset seat for this purpose as indicated at 22. The ball "B" which may be of polished steel or other relatively heavy material may be projected against this rebounding 25 device in any suitable manner, but for this purpose I preferably provide a guiding device 23 consisting of two generally parallel metal rods 24 fixed to a handle 25, these rods being spaced apart properly to form a 30 runway for the ball; this guiding device being used as seen in Fig. 1, by holding the same at a proper incline for the ball to gain momentum, and just back of the pins 18.

It will be noted that by providing the ball 35 rebounding edge or surface in the form of a segment of a circle or like concave outline, all the pins except the one head pin opposite the center of the rebounding cushion must be taken by an angle shot, and the difficulty in 40 finding the right point for this purpose and getting the right angle tends to make the game difficult to a degree so that it is interesting for skilled players, while at the same time being responsive to the degree of skill 45 and dexterity exhibited by the respective players in a game so as to be a game with a major component of skill rather than of chance.

I am aware that the invention may be embodied in other specific forms without departing from the spirit or essential attributes thereof and I therefore desire the present embodiment to be considered as illustrative and not restrictive, referring to the appended claims rather than to the foregoing description to indicate the scope of the invention. 50 55

Having described my invention, what I claim as new and desire to secure by Letters Patent is:

1. Apparatus of the kind described comprising a base presenting a relatively long and narrow plane alley surface, having a pit at the forward end and gutters along the sides thereof, and a ball rebounding element extending transversely of said alley at the rear end thereof, said element presenting a resilient front edge with a relatively rigid backing, said edge being formed on an arc of relatively small curvature. 70

2. Apparatus of the kind described comprising a base presenting a relatively long and narrow plane alley surface, having a pit at the forward end and gutters along the sides thereof, and a ball rebounding element extending transversely of said alley at the rear end thereof, said element presenting a resilient front edge with a relatively rigid backing, said edge being formed on an arc with a radius extending substantially to the other end of the alley surface. 75

3. Apparatus of the kind described comprising a base having a top presenting a relatively long and plane alley surface with a pit at its forward end and gutters along the sides thereof, the front portion of said alley surface having indicia to denote locations for ten-pins, and a ball rebounding member extending across the rear of said alley surface, said member presenting a resilient front edge formed and held in an arc whose radius extends approximately to a central portion of said ten-pin indicia. 85 90

In testimony whereof, I have signed my name to this specification.

CHARLES W. COFFIN.
